(57) **CLAIM**

The ornamental design for a drug package, substantially as shown and described.

DESCRIPTION

FIG. 1 is a front top right perspective view of a drug package showing our new design;

FIG. 2 is a back top left perspective view thereof;

FIG. 3 is a top view thereof;

FIG. 4 is a bottom view thereof;

FIG. 5 is a front view thereof;

FIG. 6 is a back view thereof;

FIG. 7 is a right view thereof; and,

FIG. 8 is a left view thereof.

The broken lines depict environmental subject matter only and form no part of the claimed design.

1 Claim, 7 Drawing Sheets(56)
